DESIGN FOR A SHEATH OR SIMILAR ARTICLE

Robert O. Green, New York, N. Y.

Application November 25, 1944, Serial No. 116,557

Term of patent 14 years

(Cl. D22—6)

To all whom it may concern:

Be it known that I, Robert O. Green, a citizen of the United States, residing at New York, in the county of Bronx and State of New York, have invented a new, original, and ornamental Design for a Sheath or Similar Article, of which the following is a specification, reference being had to the accompanying drawing, forming a part thereof.

In the drawing:

Fig. 1 is a plan view of a sheath or similar article showing my new design;

Fig. 2 is a side elevational view thereof;

Fig. 3 is an end view thereof.

The rear of the sheath is plain.

I claim:

The ornamental design for a sheath or similar article, as shown and described.

ROBERT O. GREEN.
